[57] CLAIM

The ornamental design for an ice cube tray, as shown.

DESCRIPTION

FIG. 1 is a front elevational view of a ice tray showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top isometric view thereof;

FIG. 8 is a bottom isometric view of that shown in FIG. 7;

FIG. 9 is a bottom isometric view thereof;

The surface pattern is partially shown in the cups of FIGS. 4, 8 and 9 for ease of illustration and is understood to repeat uniformly.
